J. EATON,
SWITCH MECHANISM FOR STARTING ELECTRIC MOTORS,
APPLICATION FILED JAN. 15, 1920.

1,357,695.

Patented Nov. 2, 1920.

Inventor:
John Eaton,

His Attorney.

UNITED STATES PATENT OFFICE.

JOHN EATON, OF SCHENECTADY, NEW YORK, ASSIGNOR TO GENERAL ELECTRIC COMPANY, A CORPORATION OF NEW YORK.

SWITCH MECHANISM FOR STARTING ELECTRIC MOTORS.

1,357,695.

Specification of Letters Patent. Patented Nov. 2, 1920.

Application filed January 15, 1920. Serial No. 351,729.

To all whom it may concern:

Be it known that I, JOHN EATON, a subject of the King of Great Britain, residing at Schenectady, county of Schenectady, State of New York, have invented certain new and useful Improvements in Switch Mechanism for Starting Electric Motors, of which the following is a specification.

My invention relates to an improved arrangement for starting electric motors, and is particularly adapted for use with alternating current motors of the squirrel cage rotor type which are controlled by connecting them to a source of low voltage for starting and then increasing the impressed voltage for running, but my invention is not limited to this particular type of motor.

The object of my invention is to provide an efficient and reliable automatic starter for electric motors by means of which motors may be controlled from a distance either manually or in response to the operation of another device. My invention provides improved means whereby the motor is first connected to the source of supply through a low voltage connection, and after a predetermined interval the motor is automatically connected to the source of supply through a full voltage connection.

My invention relates to features of construction and arrangement which will be explained fully hereinafter and particularly pointed out in the claims.

For a better understanding of my invention, reference is had to the accompanying drawings which illustrate in diagrammatic form an embodiment of my invention, and in which the electric motor M of the alternating current squirrel cage rotor type is adapted to be connected to the source of supply 10 through an intermediate low voltage connection of the auto-transformer 11 by means of the electromagnetic switch or contactor 12. The motor is adapted to be connected directly to the source of supply by means of the electromagnetic switch or contactor 13. The master switch for controlling these contactors comprises the starting push button switch 14 having two contact disks adapted to contact with their respective stationary contacts, the upper disk 15 and the lower disk 16 being connected together by means of the spring 17 which is compressed when the push button is depressed. The disks are mounted so as to

be free to slide on the supporting stem. Connected to the push button switch is a dash pot 18 which is biased to the position shown in the drawing by means of a spring 19, and is so arranged that when the push button is depressed, valve 20 of the dash pot will open and the resistance to the movement of the push button will be little more than the resistance offered by the spring 19. When pressure is released from the push button, the upper contact disk 15 will immediately break engagement with its corresponding contacts due to the compression of spring 17, but the lower contact 16 will not break engagement with its contacts until the collar 21 on the stem of the dash pot lifts the contact disk due to the piston of the dash pot rising by reason of the force exerted by the spring 19. A resistor 22 is provided for reducing the current in the coil circuit of the electromagnet switch 12 when the push button 14 is released after having been depressed. A pivoted mechanical interlock 23 is provided for preventing both the contactors 12 and 13 being closed at the same time, and also for the purpose of establishing the circuit for the winding of contactor 13 when the contactor 12 closes.

As thus constructed and arranged, and with the parts in the position shown in the drawing, the operation of my invention is as follows: In order to start the motor, the push button 14 is depressed, thereby compressing the spring 17 and the spring 19 so as to cause the contact disk 16 to make engagement with its contacts at about the same time that the contact disk 15 makes engagement with its contacts, and causing the piston of the dash pot to be moved to its lower position against the bias of the spring 19. The winding of the electromagnet switch will thus be connected to the source of supply and the switch will close, thereby connecting the motor to the source of supply through the reduced voltage tap of the auto-transformer 11. The motor will start and by reason of the fact that it is supplied with current at a lower potential than full line potential, the current taken will not be in excess of the proper value. As soon as the push button 14 is released, the contact disk 15 will break engagement with its contacts due to the compression of the spring 17 and the winding of the contactor 12 will be connected to the source of

supply through the resistor 22, thereby maintaining the contactor closed with a reduced current in its winding circuit. It will be noticed that the contactor 12 in closing establishes a circuit for the winding of contactor 13 through the insulated tip 24 on the contactor 12, the mechanical interlock 23 and the insulated tip 25 on the contactor 13. The contactor 13 will not close, however, until the contactor 12 is automatically opened through the operation of the dash pot, since the pull of the winding of contactor 12 is sufficient to hold this contactor closed despite the force tending to open the contactor exerted by the contactor 13 through the pivoted mechanical interlock 23. After a predetermined interval, which is determined by the setting of the dash pot 18, the collar 21 will automatically lift the contact disk 16 and open the connection of the winding of contactor 12 to the source of supply. The contactor 12 will open and contactor 13 will thereby be permitted to close and connect the motor directly to the source. The motor can be stopped at any desired time by depressing the normally closed stop push button 26.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. Means for controlling an electric motor, comprising two electromagnetic switches, the first for causing the motor to be supplied with current at one potential and the second for causing the motor to be supplied with current at a higher potential, a normally open master switch temporarily closed to effect the closing of the first electromagnetic switch and then automatically returned to its initial open position after a predetermined interval of time, and means whereby the first electromagnetic switch is opened and the second is closed responsively to the return of the master switch to its initial open position.

2. Means for controlling an electric motor, comprising two electromagnetic switches, the first for causing the motor to be supplied with a current at one potential and the second for causing the motor to be supplied with current at one potential and the manually operated normally open master switch for said electromagnetic switches, means for automatically returning the master switch to its initial open position a predetermined interval of time after it is closed, and connections whereby the first

electromagnetic switch is energized to close in response to the closing of the master switch, and the first electromagnetic switch is opened and the second is automatically closed responsively to the return of the master switch to its initial open position. 70

3. Means for controlling an electric motor, comprising two electromagnetic switches, the first for causing the motor to be supplied with current at one potential and the second for causing the motor to be supplied with current at a higher potential, a master switch biased to its open position, means whereby the master switch is movable quickly to the closed position against its bias and is retarded in its return movement to the open position in accordance with its bias, and connections whereby the first electromagnetic switch is energized to close in response to the closing of the master switch, 85 and the first electromagnetic switch is opened and the second is automatically closed responsively to the return of the master switch to its initial open position. 80

4. Means for controlling an electric motor, comprising two electromagnetic switches, the first for causing the motor to be supplied with current at one potential and the second for causing the motor to be supplied with current at a higher potential, a master switch for said electromagnetic switches, means for automatically opening the master switch a predetermined interval of time after it is closed, and connections whereby the closing of the master switch energizes 100 the first electromagnetic switch to close and thereby energize the winding of the second electromagnetic switch, whereupon the deenergization of the winding of the first electromagnetic switch after a predetermined 105 interval of time effects the closing of the second electromagnetic switch.

5. Means for controlling an electric motor, comprising two electromagnetic switches, the first for causing the motor to be supplied with current at one potential and the second for causing the motor to be supplied with current at a higher potential, an interlock for preventing both switches from being simultaneously closed, a master switch for 110 said electromagnetic switches, means for automatically opening the master switch a predetermined time after it is closed, and connections whereby closing the master switch energizes the first electromagnetic 120 switch to close and thereby energize the winding of the second electromagnetic switch through the said interlock, whereupon the deenergization of the first electromagnetic switch after a predetermined interval of time permits the second electromagnetic switch to close. 125

6. Means for controlling an electric motor, comprising two electromagnetic switches, the first for causing the motor to be sup- 130

plied with current at one potential and the second for causing the motor to be supplied with current at a higher potential, a mechanical interlock for preventing the simultaneously closing of both switches, a push button switch for controlling said electromagnetic switches, means for automatically opening the push button switch a predetermined time after it is closed, and connections whereby the first electromagnetic switch is energized to close upon the closing of the

push button switch and the winding of the second electromagnetic switch is thereby energized through the said mechanical interlock, whereupon the second electromagnetic 15 switch is closed and first opened by the automatic opening of the push button switch after a predetermined interval of time.

In witness whereof I have hereunto set my hand this 13th day of January, 1920.

JOHN EATON.
